No. 798,859.

PATENTED SEPT. 5, 1905.

R. E. ACKLEY & A. E. HIX.
WIRE BENDING MACHINE.
APPLICATION FILED APR. 8, 1905.

UNITED STATES PATENT OFFICE.

RAYMOND E. ACKLEY, OF ROCKFORD, AND ALBERT E. HIX, OF KINGSTON,
ILLINOIS.

WIRE-BENDING MACHINE.

No. 798,859.

Specification of Letters Patent.

Patented Sept. 5, 1905.

Application filed April 8, 1905. Serial No. 254,551.

To all whom it may concern:

Be it known that we, RAYMOND E. ACKLEY, a resident of Rockford, in the county of Winnebago, and ALBERT E. HIX, a resident of 5 Kingston, in the county of Dekalb, State of Illinois, citizens of the United States, have made a certain new and useful Invention in 10 Wire-Bending Machines; and we declare the following to be a full, clear, and exact description of the same, such as will enable others skilled in the art to which it appertains to 15 make and use the invention, reference being had to the accompanying drawings, and to letters of reference marked thereon, which form a part of this specification.

Figures 1, 2, 3, and 4 are perspective views of my invention with parts in four positions assumed in bending the link-eye in form. Fig. 5 is a perspective view of the rod *h*, &c., removed from the tubular guide and in the position shown in Fig. 4. Fig. 6 is a perspective view of the tubular guide. Fig. 7 is a section on the line 7 7, Fig. 6.

The invention has relation to machines for 25 making interlocking rings or loops upon wires or strips of pliable metal; and it consists in the novel construction and combinations of parts, as hereinafter set forth.

In the accompanying drawings, illustrating 30 the invention, the letter *a* designates a frame to which is secured a tubular guide *b*, having an axial extension *c*. At the side of the upper end or commencement of the extension *c* is located a stop or gage *d*. The 35 axial extension *c* is formed with an opening *e*, extending longitudinally, and such opening is bounded by a spirally-extending margin *f*, which is connected with the interior tubular bending-surface of the extension by a rounded 40 surface, as at *g*.

Engaging the tubular guide *b* is a rod *h*, which is designed to have motion of reciprocation through said tubular guide and its axial extension. This rod is made with a continuation 45 or mandrel *k* of smaller diameter, such mandrel joining the rod at its shoulder *m*, which is annular. The mandrel or continuation *k* is provided with a cam end *p*, having

a flattened guide-face *n*, whereby the wire or strip to be bent is guided transversely to the 50 gage. The flattened cam end *p* joins the mandrel *k* at a terminal shoulder *s*. The mandrel is provided with a longitudinal notch or recess *z*, sunk into its peripheral surface.

When the rod *h* is pushed through the tubular guide *b* sufficiently to bring the guide-face *n* of the cam end *p* opposite the gage, the end of a pliable wire or strip *t* is passed transversely until it touches the gage. The rod is then turned half around and is given 60 motion of reciprocation. The annular shoulder *m* engages the bent portion of the wire or strip, and the latter is carried downward along the interior of the tubular forming or bending extension *c* in such wise that the end 65 of the wire or strip is by means of the spiral margin or cam edge of the opening *e* partially bent around the mandrel *k* of said rod. The loop or eye of another wire or strip (indicated at *w*) now being pressed into the notch 70 *z* of the mandrel, the downward movement of the rod is continued until the end of the tubular extension of the guide is reached, when 75 the work will be discharged and the eye of the first-mentioned wire or strip will be found completely formed and interlocked with that of the wire or strip last referred to.

In the operation above described it is apparent that the initial bend of the wire is made by rotation of the cam end of the mandrel, which makes a bend in the wire, whereby it is enabled to engage the mandrel *k* and the annular shoulder *m*. Thereafter the work is performed by reciprocation of the rod through the operation of the notched mandrel 85 and the spiral cam of the tubular extension *c*.

Having thus described our invention, what we claim, and desire to secure by Letters Patent, is—

1. In a device for bending wire, the combination with a shouldered and notched mandrel, of a gage, and a tubular guide having an axial extension provided with a longitudinal opening having a spiral cam-margin, substantially as specified. 90

2. In a device for bending wire, the com- 95

bination with a mandrel having a notched shoulder, of a gage or stop, a tubular guide having a spiral cam extension, means for making an initial bend in the wire, and means 5 for giving motion of reciprocation, substantially as specified.

3. In a device for bending wire, the combination with a tubular forming-shell having a longitudinal spiral cam, of a rod having a 10 shoulder and extending therefrom a terminal notched mandrel, substantially as specified.

In testimony whereof we affix our signatures in presence of two witnesses.

RAYMOND E. ACKLEY.

ALBERT E. HIX.

Witnesses to signature of Raymond E. Ackley:

A. E. FISHER,
W. H. BROGUNIER.

Witnesses to signature of Albert E. Hix:

Mrs. J. A. McCOLLOM,
STUART SHERMAN.
